UNITED STATES PATENT OFFICE

ISADORE GOLDMAN AND JACOB COHEN, OF CHICAGO, ILLINOIS

ATTACHMENT FOR IRONING MACHINES

Application filed February 24, 1930. Serial No. 430,603.

There is a common type of ironing machine in which the work is passed over the top of a steam chest under a series of rollers, back underneath and in contact with the chest, and then, while held out of contact with the chest, to a delivering point at the end of the machine opposite that at which the work enters the machine. One of the objections to these machines is that the work, particularly when starched, becomes wrinkled while travelling back and forth underneath the chest, and therefore requires further treatment before it is ready to be delivered to the customer. This difficulty is so pronounced in the case of starched work that in some laundries these machines are not used on any work except that which is unstarched.

The object of the present invention is to provide a simple and novel attachment for machines of the type just described which will insure that the work, whether starched or not, will leave the same in a smooth unwrinkled condition.

It is customary, in machines of this type, to have a number of endless strings or narrow tapes, to which we shall refer as cords, passing along the chest underneath the rollers and back across the tops of the rollers, to serve as belts to hold the work on the chest in the gaps between the rollers. We have found that the problem of overcoming wrinkling while the work is carried along by the aprons may be solved by employing similar cords throughout the entire distance that is travelled by the work in passing back and forth underneath the chest. The cords under the chest may conveniently be continuations of those already in use, so that there will be a single set of endless cords having portions above the chest to function as heretofore and, in addition, other portions that insure that the work will be held flat while completing its travel after passing down from the top of the chest to the under side.

The various features of novelty whereby our invention is characterized will hereinafter be pointed out with particularity in the claims; but, for a full understanding of our invention and of its objects and advantages,

reference may be had to the following detailed description taken in connection with the accompanying drawings, wherein:

Figure 1 is a top plan view of a machine equipped in accordance with our invention; Fig. 2 is a side view; and Figs. 3 and 4 are vertical longitudinal sections, on a larger scale, showing respectively the rear and the front ends of the machine.

Referring to the drawings, 1 represents any usual or suitable horizontal steam chest above which are a series of transverse rollers 2, of which six are shown. 3 and 4 are endless aprons of about the same width as the chest. The apron 3 passes over a roll 5 lying in advance of the front end of the chest, and over another roll 6 lying in rear of and above the chest. The roll 5 is located at such an elevation that the upper run of the apron will be in contact with the under side of the chest. The lower run of the apron passes over a guide roll 7 at the rear end of and below the chest. The apron 4 passes over a roll 8 lying above and near the roll 5, over a second roll 9 lying below and forwardly of the roll 5, over a roll 10 lying at some distance below the roll 7 at the rear end of the machine, and over a roll 11 lying rearwardly from the roll 6. All these parts are of old and well-known construction. The work is fed into the front end of the machine between the right hand roller 2, in Figs. 1 and 2, and the chest, and is carried along across the top of the chest and delivered at the rear end of the chest between the adjacent part of the apron 3 and the rear edge or side of the chest; being carried along underneath the chest by the upper run of the apron to the front end of the machine, where it is gripped between a part of the apron 4 and the apron 3 and is carried back between the two aprons to the rear end of the machine where it is discharged above the top of the roll 11.

Cords 12, serving the same purpose as the endless cords heretofore employed, extend lengthwise of the machine between the rollers 2 and the chest. Additional cord means are provided, however, along the entire path of travel of the work while in the machine. This may conveniently be accomplished by

greatly lengthening the usual cords so that they will pass back and forth underneath the chest as well as above the same.

In the arrangement shown, there is a transverse guide device located above the roll 11 at the rear end of the machine. This guide device comprises a long transverse rod or bar 13 carried upon the ends of brackets 14 projecting rearwardly from the frame 15 of the machine, a series of radial arms 16 fixed to the rod or bar and having their ends terminating a little above and not far from the roll 11. On the free end of each arm is a small guide wheel 17 rotatable about an axis transverse to the machine. Each endless cord 12 extends from the front end of the machine over the steam chest to the rear end, down the rear face of the chest, between the under side of the steam chest and the upper run of the upper apron 3 to the front end of the machine, around the roll 5 between the two aprons, back to the rear end of the machine between the lower run of the upper apron and the upper run of the lower apron, over one of the wheels 17, and across the tops of the ironing rollers to the front end of the machine.

In Figs. 3 and 4 we have illustrated the manner in which the work is carried through the machine. A piece of work A is shown in the act of entering the machine in Fig. 4, under the first ironing roller and between the cords 12 and the top of the chest. In Fig. 3 the work has almost completed its passage over the top of the chest and is being carried over the rear face of the chest and underneath the same by the cords. By the time the work reaches the under side of the chest it is being pressed against the latter by the upper run of the upper apron, so that it is carried along underneath and in contact with the chest to the front end of the machine where, as in the case of the piece of work B in Fig. 4, it is carried down between the aprons over the roll 5. From that point, the cords 12 now overlying the same, the work is carried to the rear end of the machine between the lower run of the upper apron and the upper run of the lower apron. When the rear end of the machine is reached, the work passes beyond the roll 7 and up between the cords and the lower apron, as indicated at C in Fig. 3, to and over the roll 11, where it is discharged from the machine.

While we have illustrated and described with particularly only a single preferred form of our invention, we do not desire to be limited to the exact structural details thus illustrated and described; but intend to cover all forms and arrangements which come within the definitions of our invention constituting the appended claims.

We claim:—

1. The combination with an ironing machine having a steam chest, rollers above and 65 cooperating with the chest, endless aprons

below the chest to receive the work at the rear end of the chest and carry it along the under side of and in contact with the chest to the front end of the machine and then back to the rear end of the machine while held out of contact with the chest: of endless flexible cords threaded through the machine and engaged with the work during the entire distance travelled by the work as aforesaid.

2. The combination with an ironing machine having a steam chest, rollers above and cooperating with the chest, a pair of endless aprons one below the other underneath the chest to carry the work under and in contact with the chest from one end to the other and then back again between meeting runs of the aprons: of endless flexible cords passing from the front end of the machine to the rear end between the rollers and the chest, under and in contact with the chest to the front end of the machine, back to the rear end between the aprons, and then upwardly and forwardly over said rollers to the front end of the machine.

3. The combination with an ironing machine having a steam chest, rollers above and cooperating with the chest, endless aprons below each other under the chest to receive the work at the rear end of the chest and carry it between one of the aprons and the chest along and in contact with the under side of the chest to the front end of the machine and then between adjacent runs of the aprons back to the rear end of the machine: of guide means at the rear end of the machine above and near the turning point of the lower apron, and endless cords extending from the front of the machine between the rollers and the chest to the rear end, underneath and in contact with the chest to the front end of the machine, between the two aprons to the rear end of the machine, over said guides, and back across the tops of the rollers to the front end of the machine.

4. The combination with an ironing machine having a steam chest, rollers above and cooperating with the chest, endless aprons below the chest to receive the work at the rear end of the chest and carry it along the under side of and in contact with the chest to the front end of the machine and then back to the rear end of the machine while held out of contact with the chest: of flexible cords threaded through the machine and engaged with the work during the entire distance travelled by the work as aforesaid.

In testimony whereof, we sign this specification.

ISADORE GOLDMAN.
JACOB COHEN.
